UNITED STATES PATENT OFFICE.

BENJAMIN J. HOOVER, OF OKOLONA, MISSISSIPPI.

RAILWAY-TIE REMOVER.

Application filed October 13, 1926. Serial No. 141,357.

This invention relates to a device especially designed for use in repairing and constructing railway tracks, the primary object of the invention being to provide means to facilitate the removal and replacement of railway ties.

An important object of the invention is to provide a device of this character which is so constructed that a railway tie may be moved from its position under the rails of a track and a tie simultaneously moved under the rails.

A still further object of the invention is to provide means for removing the ballast at the end of the tie being removed, to facilitate the removal of the tie.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of the device showing the device in the act of removing and replacing a tie.

Figure 2 is a longitudinal sectional view through the device.

Figure 3 is a plan view of the device.

Figure 4 is a sectional view taken on line 4-4 of Figure 2.

Referring to the drawings in detail, the device includes an elongated body portion indicated generally by the reference character 5, the same being substantially oblong in cross section and hollow to receive the bar 6 designed to move longitudinally through the body portion 5.

At each end of the body portion 5 and extending from the lower surface thereof, are spaced lugs 7, the spaces between the lugs being equal to the width of the tread of the rail on which the body portion is positioned, so that movement of the body portion 5, transversely of the rails will be absolutely prevented.

This bar 6 is formed with a head 7' that has a vertical rib 8 dovetailed to fit within the opening of the removable plow 9 shown as positioned at the front end of the bar 6. A set screw indicated at 10 extends through the head and has its forward end contacting

with the plow to set up a binding action between the head and plow to prevent movement of the plow when the same has been positioned.

In connection with this construction, it might be stated that the plow 9 is removable and is only used when it is desired to remove the ballast at the end of the tie, and which usually lies in the path of travel of the tie which is being slid from its position under the rails.

Formed along the upper edge of the bar 6 are ratchet teeth 11 that are engaged by the pawls 12 carried at the lower ends of the levers 13, which levers are pivotally mounted between the upstanding ears 14, forming a part of the body portion.

As shown, the upper wall of the body portion 5 is partly cut away to expose the ratchet teeth, so that the operator may by glancing through the cut away portions in the upper surface view the action of the pawls. Secured to the head are chains 15 that extend through the head, the ends thereof having connection with the forward ends of the rods 16 that are disposed on opposite sides of the tie being removed, the rear ends of the rods being connected with the chain 17 that has its intermediate portion spiked to the tie being removed, which spike is indicated by the reference character 18.

The ends of this chain 17 when the device is in use, are spiked to the tie which is being placed under the rails, the tie being placed under the rails being indicated by the reference character 19.

In the use of the device, the body portion is positioned over the rails of a track in a manner as illustrated by Figures 1 and 2 of the drawings, whereupon the chains and rods are positioned as previously described, it being obvious that if the ballast rises to a point adjacent to the upper surface of the tie being removed, the person operating the device may position the plow 9 on the head, after a portion of the ballast has been removed to provide a clearance for the plow.

The levers 13 are now operated to cause the pawls 12 to engage the teeth and move the bar 6 in the direction of the arrow as indicated in Figure 1.

It will thus be seen that the tie will be slowly removed and the new tie will be gradually moved to its position under the rails where it may be spiked to the rail in the usual and well known manner.

It might be further stated that ropes or other flexible means such as indicated at 20 connect the pawls and levers in such a way that when the levers are moved to predetermined positions, the pawls are automatically moved to disengage the teeth of the bar 6 so that the bar may be readily slid to its position within the body portion 5.

From the foregoing detail description it 10 is thought that a further detail description as to the operation of the device is unnecessary.

I claim:

1. In a device of the character described, a hollow body portion adapted to be positioned on the rails of a railway track, a bar movable through the body portion and having a depending head, a chain carried by the head and adapted to operate to remove a tie positioned under the rails, and means 15 for securing a tie to the tie being removed, to cause the last mentioned tie to be positioned under the rails.

2. In a device of the character described, a hollow body portion, means for positioning the body portion on the rails of a railway track to prevent movement of the body portion transversely of the rails, a bar movable through the body portion, said bar having teeth formed on the upper edge 25 thereof, levers carried by the body portion and having pawls contacting with the teeth to move the bar longitudinally of the body portion, means for transmitting movement 30 of the bar to a tie being removed, and means

for transmitting movement of the tie being 35 removed to a tie being positioned under the rails.

3. In a device of the character described, a hollow body portion, said body portion adapted to be positioned on the rails of a 40 railway track, a movable bar operating through the body portion, a head formed at one end of the bar, means carried by the body portion and engaging the bar for moving the bar longitudinally of the body portion, a chain connected with the head, rods having connection with the chain, said rods extending to points adjacent to one end of a tie being removed by the device, a chain connected with the rods, and said chain 45 adapted to be spiked to a tie replacing the tie being removed.

4. In a device of the character described, a body portion, said body portion adapted to be positioned on the rails of a railway 55 track, a bar supported by the body portion, means for moving the bar longitudinally of the body portion, a head forming a part of the bar, a plow removably supported on the head, means for securing the head to a tie supported under the rails, to move the tie 60 when the bar is moved, and means for securing a tie to the first mentioned tie to move therewith.

In testimony that I claim the foregoing as 65 my own, I have hereto affixed my signature.

BENJAMIN J. HOOVER.
